UNITED STATES PATENT OFFICE.

JACOB GOGEL, OF TOLEDO, OHIO.

TIRE-HEATER.

1,082,515.

Specification of Letters Patent.

Patented Dec. 30, 1913.

Application filed August 16, 1912. Serial No. 715,372.

To all whom it may concern:

Be it known that I, JACOB GOGEL, a citizen of the United States, and a resident of Toledo, in the county of Lucas and State 5 of Ohio, (post-office address, No. 236 South Erie street, Toledo, Ohio,) have invented a certain new and useful Tire-Heater; and I do hereby declare the following to be a full, clear, and exact description of the invention, 10 such as will enable others skilled in the art to which it appertains to make and use the same, reference being had to the accompanying drawings, and to the characters of reference marked thereon, which form a part of 15 this specification.

My invention relates to tire heaters, and particularly to those of the gas burning type, but is not restricted to such use as it may be used in any connection for which it 20 or the parts thereof may be adapted or appropriate.

The object of my invention is the provision of an improved heater of the character described, which is simple and efficient in 25 its construction and operation, and easily and quickly adjustable and regulable to suit tires of different widths and diameters, and which is adapted to mix the air and gas at the point of combustion, thus preventing 30 liability of back-firing and explosion within the burner and supply connections thereto.

The invention is fully described in the following specification, and while, in its broader aspect, it is capable of embodiment 35 in numerous forms, a preferred embodiment thereof is illustrated in the accompanying drawings, in which,—

Figure 1 is a perspective view of a tire heater embodying my invention. Fig. 2 is 40 an enlarged central vertical section of a burner of the apparatus from front to rear thereof. Fig. 3 is a section on the line α , α in Fig. 2. Fig. 4 is an enlarged plan of one-half of the apparatus and Fig. 5 is a view 45 of the apparatus shown in Fig. 4, a part of which is shown in elevation and a part is shown as a central vertical section thereof.

Referring to the drawings, 1 designates the table of the heater and is shown as being made up of a plurality of sectoral sections 2, which have their side edges fitted closely together to co-operate to form a circular table and are retained in assembled 50 relation by an external uniting band 3, and 55 by the bolting together or otherwise suitably attaching of the abutting downwardly

flanged side edges of the sections. The abutting edges of the table sections 2 are each longitudinally recessed in registering relation to provide a radial slot 4 between the edges of the adjoining sections, as best shown in Fig. 4. The table 1 is supported in its proper position by a plurality of legs 5, which depend therefrom.

A burner 6 is mounted on the table 1 for 60 each of the slots 4 therein and has its air and gas supplying parts working downward through the registering slots 4 for longitudinal movement therein as the burner is radially shifted to suit the diameter of the 65 tire to be heated. These burners are preferably of multiple story construction with control valves for each story thereof to enable one or more of the stories to be used at a time as the width of the tire being heated 70

75 may require. In the present instance each burner is shown as comprising a face plate or block 7, preferably of fire-brick, which is carried by a casing part 8, on the rear side of which casing part is provided a gas-chamber 9 for each story of the burner, such chambers being arranged in superposed order and connected by passages 10, in each of which is located a plug or other suitable form of valve 11. One of these valves is 80 also located in the nipple 12 which projects downward from the lower gas-chamber 9 through the registering table slot 4, and has connection through a hose or pipe 13 with a manifold or supply pipe 14, which extends 85 around the base portion of the apparatus 90 being attached to the legs 5, and has a valve-controlled connection with a suitable source 95 of gas supply. On the back of the casing which forms the gas-chambers 9 and communicating parts is secured or formed a casing part 15, which provides a transversely broadened air-chamber 16 at the rear of each gas-chamber 9, and a connecting passage 17 between the superposed air-chambers. A slide valve 18 is located between 100 each pair of air-chambers to enable them to be cut off from each other as may be desired. The lower air-chamber has a nipple 19 extending downward therefrom through 105 the registering table slot 4 and connected by a pipe 20 to an air-blast distributing head 21, which is located below the table 1 centrally thereof. The pipes 20 extend radially from the distributing head 21 to the 110 respective burners and are of sectional telescopic form to adapt them to shorten and

lengthen as the burners are radially adjusted relative to the table center. The distributing head 21 has its bottom preferably of downwardly-projected conical form with a pipe 22 leading to the center thereof from any suitable air blast creating means, and the top of such head is also preferably of inwardly projected conical form with its apex in axial vertical register with the air inlet opening of the head to cause the blast, which is discharged into the head from the pipe 22, to be equally distributed to all sides of the head, whereby all burners will receive an equal supply of air.

15 Each gas-chamber 9 of a burner has a plurality of discharge nozzles or tubes 23 extending forward therefrom through the plate or block 7, and each air-chamber 16 has a plurality of discharge nozzles or tubes 24, projected forward therefrom through the gas-chamber 9 in advance thereof and into registering gas-discharge nozzles 23, an air nozzle 24 being provided for each gas nozzle 23. The nozzles 23 and 24 are in concentric spaced relation, with the air-nozzles 24 preferably terminating short of the discharge ends of the gas-nozzles 23, whereby the discharge of gas from the respective gas chambers through the nozzles 23 20 around the air nozzles is augmented by the discharge of air from the nozzle 24, as is apparent, the mixing of the air and gas taking place at the point of combustion instead of being mixed in bulk within the burner before discharging the same therefrom. The mixing of the air and gas without the burner and at the point of combustion prevents back-firing and explosions within the burner, and supply connections, 25 thus overcoming an objectionable feature which is present in burners of this class commonly employed.

30 The face of each burner is provided at its top and bottom edges with inwardly projecting segmental flanges 25, and intermediate such flanges with a plurality of inwardly projecting spacing studs 26 which are intended to coact with the periphery of a tire being heated to prevent the burners 35 from being moved too close to the same. The flanges 25 tend to confine the flames from the burner in the space between the faces of the burners and the tire.

35 In the use of my improved tire heater, a tire is placed upon the table 1 within the burners 6 and the burners adjusted to properly space them from the tire. Should the tire be too small for all of the burners to be moved inward to properly spaced position 40 relative thereto, alternate ones of the burners may be inwardly adjusted for such purpose. Before turning on the gas and air blast, the valves 11 and 18 of the burner, or certain ones thereof, are regulated to admit 45 gas and air to all of the chambers 9 and 16,

or certain ones thereof, as the width of the tire to be heated may require, thus adapting the burners to operate as an entirety or enabling a cutting off of one or more of the upper sections, as desired. This being done 70 the gas and air are turned on, causing gas to be discharged from the burner chambers 9 through the nozzles 23 and air to be discharged from the chambers 16 through the nozzles 24, the mixture and combustion of 75 the air and gas taking place without the burner.

80 It is found in practice that this construction of burner and the manner of discharging the gas and air therefrom provide a powerful blast furnace or heater which effects a rapid heating of a tire to the desired temperature.

85 The building of the table in sections enables the same to be quickly assembled or knocked down and compactly packed for shipping or storing, and also enables the several parts thereof to contract or expand under changing temperature conditions without breaking. The band 3 which 90 encircles the periphery of the table permits the table to expand when heated.

95 I wish it understood that my invention is not limited to any specific construction or arrangement of the parts except in so far as such limitations are specified in the claims.

Having thus described my invention, what I claim as new and desire to secure by Letters Patent, is,—

100 1. A gas burner having a vertical face, a plurality of superposed communicating air chambers and a plurality of superposed communicating gas chambers, said air and gas chambers coöperating in pairs to form operative burner sections each having a discharge nozzle in said face, and means controlling the flow of air and gas to the respective chambers.

105 2. A burner comprising a plurality of gas chambers and a plurality of air chambers in communication, respectively, with sources of gas and air supply, means selectively operable for closing each of said chambers to their respective sources of supply, and a discharge nozzle projected from each of said 110 chambers with the discharge nozzle of each air chamber projected into a discharge nozzle of a gas chamber.

115 3. A burner having a plurality of air and a plurality of gas chambers, means for controlling the supply of air and gas to each of said chambers of the respective sets, and a nozzle projected forward from each of said chambers with the nozzle of one chamber of a set projected through the other chamber 120 and into its discharge nozzle, substantially as described.

125 4. A burner having an air conduit in communication with a source of air supply, a gas conduit in communication with a source of 130

gas supply, valves in said conduits for dividing each into a plurality of compartments, and nozzles projected from said compartments with each air compartment nozzle 5 projected into a gas compartment nozzle.

5. A burner having a plurality of superposed gas chambers in valve-controlled communication, a plurality of superposed air blast chambers in valve-controlled communication, said air and gas chambers being arranged one in advance of the other, and discharge nozzles projected forward from the respective chambers with the nozzles from the rear chambers projected into the nozzles 10 from the forward chambers.

6. A burner having a facing of fire-brick, a plurality of superposed communicating gas chambers attached to the rear end of said facing, a plurality of communicating air blast chambers attached to the rear of the gas chambers, valves controlling the communication between the communicating chambers, and discharge nozzles projected 15

forward from the respective chambers through said facing with the nozzles from 25 the air chambers projected through the gas chambers in advance thereof and into their nozzles.

7. In an apparatus of the class described, a plurality of burners each being divided 30 into a plurality of burner sections having a plurality of inter-communicating gas chambers in communication with a source of gas supply and a plurality of intercommunicating air blast chambers in communication 35 with a source of air supply, and means for cutting each of the said chambers out of communication with their respective sources of supply.

In testimony whereof, I have hereunto 40 signed my name to this specification in the presence of two subscribing witnesses.

JACOB GOGEL.
